UNITED STATES PATENT OFFICE.

WILLIAM M. GARWOOD, OF PITTSBURGH, PENNSYLVANIA, ASSIGNOR TO MILLER SAW-TRIMMER COMPANY, OF PITTSBURGH, PENNSYLVANIA, A CORPORATION OF PENNSYLVANIA.

BEVELING DEVICE.

1,385,782.

Specification of Letters Patent. Patented July 26, 1921.

Application filed January 22, 1920. Serial No. 353,347.

To all whom it may concern:

Be it known that I, WILLIAM M. GARWOOD, a citizen of the United States, residing at Pittsburgh, in the county of Allegheny and State of Pennsylvania, have invented certain new and useful Improvements in Beveling Devices, of which the following is a specification.

My invention pertains to devices for cutting the ends of type slugs, brass rule or the like to a bevel.

In printing, when it is desired to set a border around a square cut, electrotype or the like, it is usual to cut four pieces of brass rule, or else four type slugs having a line or ornamental characters upon the printing edge, to the proper length, mitering the ends so that the pieces will fit together like a box around the cut or the like. For this and kindred work, the lengths of the cut and mitered slugs or rule must be very accurate and the mitering must be perfect. It is the principal object of my invention to provide means by which cutting and beveling of the above character can be easily, quickly and accurately performed.

By way of example, I have described in the following specification, and shown in the accompanying drawings, a form of device embodying my invention. In these drawings:

Figure 1 is a plan of a machine for cutting type slugs having applied thereto a device constructed in accordance with my invention;

Fig. 2 is an enlarged fragmentary plan showing the manner of positioning the slugs to be beveled, with respect to the spacing gage;

Fig. 3 is an enlarged plan of the spacing gage, showing the means for adjusting its position for use in connection with slugs of different thicknesses;

Fig. 4 is a section on the line 4—4 of Fig. 3, looking in the direction of the arrows;

Fig. 5 is a plan showing the position of the parts for the first beveling cut; and

Fig. 6 is a plan showing the position of the parts for the second beveling cut.

My improved device is very well adapted for use in connection with such a slug-cutting machine as is described in Patent No. 986,485 issued to H. G. Miller March 14, 1911 for vises. Such a slug-cutting ma-

chine comprises a support carrying a fixed table 10^a and a movable table 11, the latter being capable of being slid to and fro in a direction parallel to the cutting plane of a rotary saw 12^a. Mounted upon the sliding table 11 is a rest consisting of a side gage 13, which is graduated to picas, and an end gage 14 extending at right angles to the side gage and slidable thereon, said end gage carrying an adjusting worm 15, graduated to points, engaging corresponding worm grooves in the side gage 13. The side gage 13 is normally positioned at right angles to the cutting plane of the saw, but it may be swung so as to assume various other angles with such plane, the most frequently used after the right angle being the forty-five degree position indicated in Figs. 5 and 6. A vise co-operates with the side gage and includes a vise-bar 16, operated by a handle 17. The end of the side gage is squared so as to provide a surface 18^a at right angles to the main slug-engaging surface 19 of the gage, and with this surface 18^a co-operates a supplemental vise 20, when the side gage is swung into the forty-five degree position. On the fixed table 10^a (Figs. 3 and 4) is mounted a member 20^a having a slug-engaging face 21 parallel with the cutting plane of the saw, and having a shank 22 extending at right angles to said plane, the bottom of said shank being formed with a tongue 23 which slidably engages a groove formed in the top of the fixed table 10^a. A cap screw 24, passing through a slot 25, extending lengthwise of the shank 22, and entering one or the other of the two holes 26 in the table 10^a, serves to hold the member in any position to which it may be adjusted. The machine, as thus far described, is old and well known in the art.

The member 20^a has heretofore been termed a "batter" and has been employed to line up the ends of type slugs by being pushed forward so as to engage the irregular slug-ends and thus bring them into line. According to my invention, I employ the member 20^a as a spacing gage, and to that end form in the shank 22 thereof a series of holes 27 which co-operate with another series of holes 28 formed in the table 10^a, these holes 28 being so spaced as to require a longitudinal adjustment of the gage member to bring each of them into alignment with its corresponding hole 27 in the shank of the

gage member. Brass rule and type slugs are purchased in standard thicknesses, measured in points, and the holes 27 are numbered, as indicated in Fig. 3, to correspond with slugs of these standard thicknesses; thus the hole numbered 2 will be employed, with its corresponding hole 28, when a slug 2 points in thickness is to be mitered, the hole numbered 10 will be used in connection with a slug of 10 points thickness, and so forth. The spacing of these holes will be readily understood from Fig. 2 of the drawings, in which the side gage is shown positioned at the forty-five degree angle with four six point slugs 31 placed in position against it, the broken line $a-b$ indicating the line of cut of the saw. The position of the holes 27 and 28 for six point slugs is such that, when brought into alinement by the pin 30, the location of the slug-engaging face 21 is such that the rear corners c of the slugs will be precisely on the line $a-b$, when such slugs are made to abut, with their front corners d , against such face. That is to say, the location of the slug-engaging face 21 is such that distance $d-e$ between it and the line of cut $a-b$ of the saw is equal to the altitude of a right angled triangle having six points as one of its shorter sides. Similarly the holes 27 and 28 for two-point slugs are so placed that, when brought into alinement by the pin 30, the slug-engaging face 21 will be spaced from the line $a-b$ a distance equal to the altitude of a triangle having two points as one of its shorter sides.

Supposing, for instance, a box having sides twenty picas and four points long is to be made from six-point slugs, to form a margin for a cut, type-matter or the like. By employing the improved device herein described, this is effected as follows: With the side gage 13 in the right angled position shown in Fig. 1, the end gage 14 is set precisely at twenty picas and four points, the slugs 31 are placed in position against the face 19 of the side gage with their ends abutting against the end gage and are locked in this position by the vise bar 16, and a cut is made by sliding the table 11 past the saw 12^a. This cuts the slugs to a length of precisely twenty picas and four points. The spacing gage 20^a, forming an abutment for the slugs, is then adjusted and the pin 30 inserted in the holes 27 and 28 corresponding to a six point slug, the side gage is swung into the forty-five degree position (Fig. 5), the slugs 31 are shifted so as to abut, with their corners d , against the face 21 of the spacing gage and are locked in that position by the vise bar 16, and a second cut is made. This second cut mites the slugs at one end without disturbing their length. The slugs are then placed against the surface 18^a of the side gage (Fig. 6),

are shifted so that the corners of their other ends abut against the face 21 of the spacing gage, are locked in this position by means of the vise 20, and a third cut is made. This third cut mites the other ends of the slugs without disturbing their length.

The operation, as described above, is very easily and quickly accomplished. There are required but one setting of the end gage, one movement of the side gage, one setting of the spacing gage, and three cuts. The operation, moreover, can be effected with great accuracy as to the predetermined final length of the mited slugs.

While I have described and shown one form of device embodying my invention, I wish it understood that changes may be made in the form described and shown, and that my invention may be embodied in other forms, without exceeding the scope thereof, as defined in the appended claims.

Having now fully described my invention, what I claim as new, and desire to secure by Letters Patent, is:

1. A device for beveling the ends of type-slugs or the like, comprising cutting means, an abutment beyond the plane of cutting of said cutting means, said abutment having a slug-engaging face, and means for adjusting said abutment to bring said face to a distance from the plane of cutting of said cutting means equal to the altitude of a right-angled triangle having the thickness of the slug to be beveled as one of its shorter sides, said adjusting means having indicia for designating the position of adjustment for slugs of varying thicknesses.

2. A device for beveling the ends of type-slugs or the like, comprising a support, a rotary saw associated with said support, a rest mounted on said support so as to be movable into and out of operative position with respect to said saw, an abutment having a slug-engaging face, means for supporting said abutment at the side of said saw remote from said rest, and means for adjusting said abutment to bring said face to a distance from the plane of cutting of said saw equal to the altitude of a right-angled triangle having the thickness of the slug to be beveled as one of its shorter sides, said adjusting means having indicia for designating the position of adjustment for slugs of varying thicknesses.

3. A device for beveling the ends of type-slugs or the like comprising a support, a rotary saw associated with said support, a rest having a slug-engaging face, mounted on said support so as to be movable into and out of operative position with respect to said saw and so as to be capable of being moved from a position in which said face extends at right angles to the cutting plane of said saw to a position in which said face extends at a different angle, an abutment

having a slug-engaging face, means for supporting said abutment at the side of said saw remote from said rest, and means for adjusting said abutment to bring its slug-engaging face to a distance from the cutting plane of said saw equal to the altitude of a right-angled triangle having the thickness of the slug to be beveled as one of its shorter sides, said adjusting means having

10 indicia for designating the position of adjustment for slugs of varying thicknesses.

4. A device for beveling the ends of type-slugs or the like comprising a support, a rotary saw associated with said support, a 15 rest having a slug-engaging face, mounted on said support so as to be movable into and out of operative position with respect to said saw and so as to be capable of being moved from a position in which said face extends 20 at right angles to the cutting plane of the saw to a position in which said face extends

at a different angle, said rest having a second slug-engaging face extending at right angles to the first-named face, an abutment having a slug-engaging face, means for supporting said abutment at the side of said saw remote from said rest, and means for adjusting said abutment to bring its slug-engaging face to a distance from the cutting plane of said saw equal to the altitude of a 25 right-angled triangle having the thickness of the slug to be beveled as one of its shorter sides, said adjusting means having indicia for designating the position of adjustment for slugs of varying thicknesses. 30

In testimony whereof I have hereto affixed my signature.

WILLIAM M. GARWOOD.
